Primary Examiner — Sandra Snapp*Assistant Examiner* — Mehri Bajoul(74) Attorney, Agent, or Firm — Kochka Law, LLC;
 Michael P. Kochka, Esq.(57) CLAIM

The ornamental design for a toss game, as shown and described.

DESCRIPTION

FIG. 1 is a perspective view of a toss game showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines of even length shown in the drawings illustrate portions of the toss game that form no part of the claimed design.
